United States Patent Office.

WARREN WHITNEY DUTCHER, OF HOPEDALE, MASSACHUSETTS, ASSIGNOR
TO DUTCHER TEMPLE COMPANY, OF SAME PLACE.

Letters Patent No. 97,895, dated December 14, 1869.

IMPROVEMENT IN LOOM-TEMPLE.

The Schedule referred to in these Letters Patent and making part of the same.

To all persons to whom these presents may come:

Be it known that I, WARREN WHITNEY DUTCHER, of Hopedale, of the county of Worcester, of the State of Massachusetts, have made a new and useful invention having reference to Loom-Temples; and I do hereby declare the same to be fully described in the following specification, and represented in the accompanying drawings, of which—

Figure 1 is a top view;

Figures 2 and 3, side elevations; and

Figure 4 is a longitudinal section of a "roller-temple" as provided with my said invention.

In carrying out my invention, I combine, with a loom-temple, a mechanism for holding back the slide thereof, when retracted within its stand; and furthermore, I so make the catch, constituting such additional mechanism, or a part thereof, that while in use it shall not only perform the function of a catch, but shall serve as a cover or guard, to prevent oil from being thrown from the stops upon the cloth that may be in the process of being woven.

By my arrangement or application of the catch, it is used, with the back-stop, in affecting the holding of the temple retracted.

The object of holding the temple retracted is to enable the weaver to remove from the warp any filling which may have been improperly introduced therein.

It occasionally happens that it becomes desirable to retract the temple, for purposes well known to weavers, such retraction and holding back having generally been accomplished by the weaver.

Furthermore, when the temple, during its advance, after a beat of the lay carries the back-stop against the front stop, oil, which may get between the two, will be liable to be spilted or thrown upon the cloth, to the detriment or damage thereof.

My catch is constructed to extend over the stops, and about in a manner to stop any such oil so rejected, and prevent it from falling on the cloth adjacent to the stand.

In the drawings—

A denotes the temple-roller and case, which is of the usual construction, and is to carry or contain a temple-toothed roller of the ordinary kind.

This case is attached to or supported by a slide or bar, B, sustained by a stand, C, in a manner to enable such bar to play or slide longitudinally therein.

A helical spring, D, applied to the slide and stand, serves to advance the slide, until a back-stop or shoulder, a, thereof may bring up against a fore-stop, b, which, in this instance, is a part of the catch E. The said catch E is jointed to the stand, or to standards C C, making part thereof, the joint-pin being exhibited at d, it going through the standards C C and the fore-stop b.

Lips f f, from the catch, extend down from its sides, and overlap opposite edges of the slider.

When the slider is retracted, in manner as shown in Figure 5, which is a longitudinal section of the temple, the catch E is to be forced downward, so as to force its rear end below the top of the back-stop a, which being brought up against the catch, will cause the temple to be held in its retracted position.

By raising the catch to its horizontal position, the temple will be set free, and will be advanced by the spring, until the back-stop may bring up against the fore-stop.

I claim, as my invention, the following, viz:

In combination with the temple, a mechanism, substantially as described, for holding back the slide, when retracted in the stand.

Also, the arrangement of the catch E, and its application to the temple, so as to operate with the back-stop a, in manner and for the purpose as set forth.

Also, the catch E, so constructed, that when in use it shall not only perform the function of a catch, or operate with the back-stop a, as set forth, but shall act as an interceptor of any oil which may be ejected from either or both the stops, or the slide between them, and prevent such oil from getting upon the cloth carried by the temple.

WARREN WHITNEY DUTCHER.
